CARGO TRAILER

Arney C. Stensrud, Middletown, Ohio, assignor to TransporTrailer, Inc., Dayton, Ohio

Filed Mar. 20, 1970, Ser. No. 21,987

Term of patent 14 years

Int. Cl. D12—10

U.S. Cl. D14—3

FIG-3

FIG. 1 is a side view of a cargo trailer showing my new design, the opposite side view being the same;

FIG. 2 is a top view thereof; and

FIG. 3 is an end view thereof, the opposite end view being the same.

I claim:

The ornamental design for a cargo trailer, substantially as shown and described.
